(57) **CLAIM**

The ornamental design for a pipe gland, as shown and described.

DESCRIPTION

FIG. 1 is a perspective view of a pipe gland according to the present design;

FIG. 2 is a front elevation view of the pipe gland shown in FIG. 1;

FIG. 3 is a section view of the pipe gland shown in FIG. 2, taken along section line 3—3;

FIG. 4 is a right elevation view of the pipe gland shown in FIG. 1, with the left elevation view of the pipe gland shown in FIG. 1 being a mirror image of FIG. 4;

FIG. 5 is a bottom plan view of the pipe gland shown in FIG. 1, with the top plan view of the pipe gland shown in FIG. 1 being a mirror image of FIG. 5; and,

FIG. 6 is a rear elevation view of the pipe gland shown in FIG. 1.

The broken lines shown herein are for illustrative purposes only and form no part of the claimed design.
